DESIGN FOR A DEVICE FOR ANALYZING COMBUSTION MOTORS

Arthur P. Warner, Beloit, Wis., assignor to
Warner-Patterson Company, Chicago, Ill., a
corporation of Illinois

Application October 21, 1939, Serial No. 87,792

Term of patent 14 years

To all whom it may concern:

Be it known that I, Arthur P. Warner, a citizen
of the United States, residing at Beloit, Rock
County, Wisconsin, have invented a new, original,
and ornamental Design for a Device for Analyzing
Combustion Motors, of which the following is
a specification, reference being had to the ac-
companying drawing, forming part thereof.

The figure is a perspective view of a device for

analyzing combustion motors, showing my new
design.

The rear of my device is substantially plain.
The characteristic features of my design reside
in the portions shown in solid lines.

I claim:

The ornamental design for a device for analyz-
ing combustion motors, as shown and described.

ARTHUR P. WARNER.
